UNITED STATES PATENT OFFICE.

EZRA F. HOPKINS, OF CHICAGO, ILLINOIS.

FLUID-FUEL FEEDER.

1,114,764.

Specification of Letters Patent. Patented Oct. 27, 1914.

Application filed February 12, 1912. Serial No. 677,145.

To all whom it may concern:

Be it known that I, EZRA F. HOPKINS, a citizen of the United States, residing at Chicago, in the county of Cook and State of Illinois, have invented certain new and useful Improvements in Fluid-Fuel Feeders, of which the following is a specification.

This invention relates to the feeding of fluids for fuel purposes into apparatus of any nature, as for example, combustion chambers of various forms of power generators, or prime movers.

It has for one of its objects the production of a device for the purpose specified, which is positive in its action, so that temporary variations with reference to the combustion chamber, such as the amount of pressure therein, will affect the rate and the manner of feeding the fuel.

Another object is to produce means operated either manually or automatically for effectively regulating the rate at which the fuel is fed, and to provide for the automatically operated means being controlled, if desired, by the speed of the engine, or other machine operated by means of the generator.

A further object is the production of such a device which will automatically compensate for the wear of its parts, and also a device which is very dependable, requiring little or no attention to keep it in good working order, and requiring but little lubricating.

A further object is to prevent all danger from back-firing, or from accidental ignition in any way of the fuel as it is being fed to the combustion chamber.

In the accompanying drawings, Figure 1 is a longitudinal central section of a low power feeder embodying features of my invention. Fig. 2 is a transverse section of the same on the line 2 2, and Fig. 3 is a similar section on the line 3 3 of Fig. 1. Fig. 4 is a perspective view of the rotating member of the feeder. Fig. 5 is a vertical central section of a modification of the feeder, which is adapted to high power uses. Fig. 6 is a plan view of same with portions in section. Figs. 7, 8 and 9 are sections of portions of the modifications of the device shown in Figs. 5 and 6.

The devices which I have illustrated and shall describe which embody features of my invention feeds liquid or gas fuel into the combustion chamber. Any fluid fuel from

the most volatile gases to the most non-volatile liquids may be used by proper adjustments, and if necessary, proper modifications in the details as described. The manner of feeding the fuel is somewhat similar to the action of a screw which is used to transport fluids or solids from one place to another. A vertical member rotates within a casing and has grooves on its periphery adjacent to the inner surface of the casing. These grooves receive the fuel, and as the member rotates carry the fuel and deliver it into receiving chambers in the inner sides of the walls of the casing. Other grooves in the rotary member receive the fuel from these chambers and deliver it into the combustion chamber, the second set of grooves in the rotating member being in a higher longitudinal plane than the first set. The first set of grooves open at their lower ends into a fuel-supplying chamber, and the second set open at their upper ends into a chamber communicating with the combustion chamber. The grooves, however, differ from the grooves of a screw in that they are all disconnected, and they are so placed that fuel is never being delivered by one set of grooves into the receiving chambers at the same time it is being received by any of the other grooves from the same chamber, and hence there is at no time open communication between the external supply of fuel and the combustion chamber. Thus back-firing is entirely prevented, and irregularities in external or internal pressure are eliminated.

The rotating member 10 of the low power feeder of Fig. 1 is shown with its grooves 11 and 12 in Fig. 4. The rotary member is preferably mounted vertically in the casing 15 with its open end upward, but it may be mounted horizontally or otherwise if desired. The grooves 11 extend downwardly and open into the annular cavity 13 which encircles the member. And grooves 12 extend upwardly and open into the chamber 19, which in turn opens into the combustion or other chamber where the fuel is to be used. The opening 14 in the casing 15 is connected in any suitable manner with a suitable supply of fuel. A pressure somewhat in excess of the average pressure in the combustion chamber acts on the gas or liquid fuel supply and causes the fuel to pass into the opening 14 through a suitable connecting pipe threaded therein. It then passes into the annular cavity 16 in the

casing encircling the rotary member and into the annular cavity 13, which at all times registers with the cavity 16. The fuel then passes into the grooves 11 and by these is delivered into a plurality of chambers 18 in the casing. These chambers are so positioned that they alternately register with individuals of the grooves 11 and 12, respectively. The fuel in the upper portion of the grooves 11, as these grooves register with chambers 18, passes into the chambers and some of the fuel in turn passes from these chambers into the grooves 12 as they register with the chambers.

15 The casing 15 is screwed, or attached in any other suitable manner, to the combustion chamber, or the chamber in which the fuel is to be used. The annular chamber 19 formed by the walls of the rotary member 10 and the casing forms part of the combustion chamber, and for convenience will hereinafter be designated as the combustion chamber. The grooves 12 open into this chamber 19 and fuel contained in these 20 grooves is constantly working upward into this chamber. This is due partly to capillary action and partly because the reduced pressure in the combustion chamber to which the fuel is exposed allows gaseous 25 portions of the fuel to expand and pass upward into the chamber. In addition the clearance between the walls of the rotary member and the casing will be sufficient to allow the external pressure to act effectively 30 on the fuel forcing it onward during its entire passage. In the meantime air or some other fluid containing oxygen under pressure enters the inlet 20 from some suitable source of supply through a connecting pipe 35 threaded therein. It then passes into the annular groove 21 in the casing. From this it passes into the transverse passage 22 and the longitudinal passage 23, and then into the combustion chamber. As the fuel evaporates and passes the upper end of the 40 rotary member 10, it mixes with the air entering the chamber through the passage-way 23 and becomes in proper condition for combustion. It will be understood that during 45 the entire process the rotary member 19 is caused to rotate in the casing 15 by some suitable means. In this instance I have used for the purpose a worm gear 24 actuated by a worm 25 fixed on a shaft 26. The shaft 50 may be operated by any suitable means.

In order to economize in the use of the fuel and to control the power output, the quantity of fuel admitted to the combustion chamber may be governed by varying the 55 speed of rotation of the member 10, by regulating the external pressure on the fuel, or by varying the capacity of the chambers 18 by means of the screws 27. In practice, more or less air or vapor will be contained 60 in the chambers 18 and this will allow

more or less fuel to be forced into the chambers by compressing the contained gas. And the greater the capacity of the chamber the greater the amount of contained gas, and the greater the amount of fuel that may be 70 forced therein. Hence by unscrewing the screws 27 the rate of feeding may be increased. The quantity of air admitted into the combustion chamber also may be regulated by the use of a regulating valve in 75 the supply pipe, or by varying the pressure on the air, or otherwise.

As the grooves 11 and 12 are not connected and are positioned on the rotating member with reference to each other so that 80 they are at no time connected by means of the chambers 18, a sufficiently closed joint is at all times maintained between the combustion chamber and the fuel supply, so that any possibility of back-firing is eliminated. As the groove 21 encircles the member 10, it allows a uniform quantity of air to pass through the passages 22 and 23 at all times. It will thus be seen that the feeding is positive in its action, being independent of any fluctuations in the internal pressure, and that the annoyance and danger, as well as waste, from back-firing is avoided. The feeder may be attached to the combustion chamber by means of 95 threads 28, or in any other suitable manner.

Where a large amount of fuel is to be used in case of high-power generators, the surface of the rotary members must be correspondingly increased in size so as to give 100 sufficient groove capacity, and also to give sufficient strength to prevent danger of torsional fracture, while allowing at the same time a sufficiently large air passage to accommodate the increased amount of air 105 required. Figs. 5 and 6 illustrate a device of this nature. The vertical member 29 is caused to rotate in the casing 30 by means of a worm gear 31 which is operated by the worm 32 fixed on the shaft 33.

Fig. 7 shows a reduced view of a modification of the operating device of the high-power feeder in which the shaft extends downwardly from the feeder. This type may be used when it is desired to drive the feeder 115 from below. In this case the shaft may have fixed thereon a pinion 35 meshing with the gear 36 encircling the member 29 which is caused to rotate in the casing 30.

The two conical surfaces of the member 120 29 and casing 30 in either of the types are held in contact with each other but are not pressed together. The member 29 is supported by a ring of balls 37 which prevents the two conical surfaces pressing too tightly 125 together. The balls are supported by a beveled ring 38 encircling the rotary member but fixed to the casing. As the balls and the ring wear by use, the rotary member sinks in the casing and thus compensates for the 130

slight wear which gradually takes place between the two members, so that the two surfaces are constantly maintained loosely in contact.

5 A member 39 provides means for attaching the feeder to a suitable object such as a cylinder of an internal combustion engine, the mixing chamber 40 in such a case forming a portion of the combustion chamber. The feeder may be attached by means of the threads 41, or by any other suitable means. This member 39 prevents the member 29 from rising in its seat, but it is not in contact therewith except when the rotary member 29, for any reason, is forced upwardly. In order to adjust the position of the member 39 to compensate for any wear between the adjacent surfaces of members 29 and 39, or members 29 and 30, 20 shims 42 may be placed between the casing and the flange 43 of the member 39 and these shims may be removed when desired. A more expensive, but more desirable method for such adjustment is shown in 25 Fig. 8 in which the member 39 is supported by the casing 30 by means of the flange 43, Fig. 5. But the adjacent surfaces 44 and 45 of the members 29 and 39 are beveled as indicated, and the member 29 is kept 30 from rising by means of balls 46. Gravitation causes the balls to sink into the aperture 47 until they press against both surfaces. As the surfaces 44 and 45 are not parallel, as wearing by the balls occur, or 35 as the rotary member sinks in its bearing, the balls will sink in the aperture and compensate for the wear, preventing rising of the rotary member. So that any wear between either of the two sets of adjacent 40 surfaces is automatically cared for.

The balls 37 and 46 are used not only to compensate for wear and to relieve friction, but they also keep the fuel feeder in operative condition in case the lubricating 45 oil is stopped. In fact the parts would operate successfully without any lubricant. However, suitable means are provided for lubrication at all desirable points. The shaft 33 is also journaled in ball bearings 48, 49 and 50. A cavity 51 provides for packing the shaft with any suitable packing material, and the material may be entered through the opening 52 and packed by means of a screw threaded therein.

55 The method of introducing fuel into the combustion chamber by means of this high-power feeder is very similar to that of the low-power feeder herein above described, but for the sake of clearness the method of the high-power feeder will now be explained in detail.

The fuel under pressure enters the feeder through the opening 53 into which is threaded the pipe 53^a and which is connected in any suitable manner to a fuel

supply. The annular groove 54 in the casing 30 and the grooves 55 and 56 in the rotary member 29 correspond to the annular groove 16 and the longitudinal grooves 11 and 12 of the low-power device. The only difference is that the longitudinal grooves 55 and 56 extend both above and below the annular groove 54. Distributed around the inner portion of the wall of the casing 29 are a plurality of chambers 56^a which correspond to the chambers 18 in the other device. The grooves 55 are spaced uniformly around the periphery of the rotary member and extend longitudinally in both directions a distance sufficient to register in their passage with the chambers 56^a. The grooves 56 are also uniformly distributed around the rotary member and also register in their passage with the members 56^a. The upper series of grooves 56 extend upwardly and open into the annular groove 58, and the lower series of grooves 56 extend downwardly and open into the annular groove 59. As the member 29 rotates the fuel is received by the groove 55 and is conveyed in these grooves to the chambers 56^a. It is then received from these chambers by the grooves 56, and from these it passes into the annular grooves 58 and 59.

Connecting the annular groove 59 with the chamber 40 is an annular cavity 60 which is formed between the inner surface of the rotary member and the outer surface of the cylindrical member 61 which is threaded into the casing and projects within the rotary member. The fuel passes upward from the groove 59 through the cavity 60 and flows along the cross-pieces 61 in the grooves 62. Similarly the fuel enters the groove 58 from the grooves 56, passes through the openings 57 to the cross-pieces 61 and into the grooves 62. In the meantime air or oxydizing fluid under sufficient pressure enters the passageway 63 from any suitable source and passes upward through openings 64 (Fig. 6) and the aperture 65. As the fuel passes down the cross-pieces it will evaporate more or less and become mixed with the air issuing through the openings 64. If, however, the fuel is not sufficiently volatile to evaporate in its passage along the grooves, it will reach the aperture 65 and there mix with the rising air and be carried up with the air in the form of a spray. When fuel of less volatility is used, the cavities 57 must be larger than when the volatility of the fuel is greater, and special provision is made for enlarging sufficiently these cavities. Annular tubes 66 are threaded into the openings 67. The outer end of each of these tubes extends upwardly and has threaded therein a screw 68. The size of the chamber within the tube may then be varied by means of this screw. These chambers will

contain at all times more or less air or vapor. This gas, by virtue of the pressure on the entering fuel will be more or less compressed and thus a greater or less quantity of fuel will be forced into the receiving chambers 57. The amount of gas therein will determine the amount of surplus fuel that will be forced into the chambers and hence will determine the amount of 10 fuel delivered to the grooves 56.

Fig. 9 shows a modified form of tube 66 which is used with variable speed engines. The screw is replaced by the plunger 69. This plunger is connected in any suitable 15 manner with a speed governor on the engine and is forced downwardly as the speed increases, thus causing less fuel to be delivered to the generator, and hence causing the power of the generator to diminish. A 20 stuffing box 70 prevents the escape of the contained air or gas. The amount of fuel and air fed may be regulated in the same way as with the low power feeder, as herein-before described.

I wish to have it understood that the invention herein set forth is capable of various other modifications, and I do not therefore limit the invention to the form and arrangement herein shown and described.

I claim as my invention:

1. A fluid fuel feeder comprising a casing, a rotary member in said casing, said casing having an inlet port therethrough, said casing having a chamber therein, said rotary 35 member having a groove therein, said groove, as the member rotates, registering alternately with said port and with said chamber, said member having a second groove therein, said feeder having a mixing 40 chamber at one end thereof, said second groove in said rotary member opening into said mixing chamber, said second groove, as the member rotates, registering with said first mentioned chamber, and means for rotating said member.

2. A rotary fuel feeder comprising a casing and a rotary member mounted in said casing, said casing having a fuel inlet port and an air inlet port therethrough, said casing having a fuel chamber therein, said rotary member having a groove therein, said groove, as the member rotates, registering alternately with said fuel inlet port and said chamber, said rotary member having a second groove therein, said feeder having a mixing chamber at one end thereof, said second groove opening into said mixing chamber, and said second groove, as the member rotates, registering with said fuel 60 chamber, said rotary member having a passageway connecting said mixing chamber with said air inlet port, and means for rotating said member.

3. A fluid fuel feeder comprising a casing and a rotary member in said casing, said

casing having a fuel inlet port, said casing having a chamber therein, said rotary member having a groove therein, said groove, as the member rotates, registering alternately with said inlet port and said chamber, said rotary member having a second groove therein, said feeder having a mixing chamber at one end thereof, said second groove opening into said mixing chamber, and said second groove, as the member rotates, registering with said first mentioned chamber, said rotary member having an air inlet port and having a passageway connecting said air inlet port with said mixing chamber, said feeder adapted to be used with an engine, and means depending upon the speed of the engine for varying the capacity of said first mentioned chamber.

4. A fluid fuel feeder comprising a casing and a member rotatably mounted in said casing, said casing having a fuel inlet port, said member having an annular groove registering with said port, said casing having an outlet port, said casing having a series of chambers in the inner side of its walls, 90 said member having a series of longitudinal grooves opening into the annular groove in said member, and registering, as the member rotates, with said chambers, said member having a second series of longitudinal 95 grooves opening at all times into said outlet port and registering as the member rotates with said chambers and means for rotating said member.

5. A fluid fuel feeder comprising a stationary member with a vertical downwardly-tapering opening, a rotary member with a tapering periphery mounted in said opening, means for rotating said rotary member, means for conveying fuel between said tapering surfaces from a fuel supply to a combustion chamber, and automatic means for compensating for the wear of said tapering surfaces, whereby said conveying means are not varied by said wear.

6. A fluid fuel feeder comprising a stationary member with a vertical tapering opening, said opening converging downward, a rotary member with a tapering periphery mounted in said opening, means 115 for rotating said rotary member, means for conveying fuel between the adjacent walls of said members, and automatic means for compensating for the wear of said taper surfaces, said automatic means comprising balls 120 resting upon said stationary member and supporting said rotary member, the surface of said stationary member upon which said balls rest being inclined downwardly.

7. A fluid fuel feeder comprising a casing, said casing having a vertical conical opening, said opening converging downwardly, a rotary member with a conical periphery mounted in said opening, means 125 for rotating said rotary member, and means 130

for conveying fuel between the walls of said casing and said member, a stationary member mounted in said casing above said rotary member, whereby said rotary member is prevented from rising, and automatic means for compensating for the wear of the adjacent surfaces of said casing and said rotary member.

8. A fluid fuel feeder comprising a casing and a rotary member in said casing, said casing having a fuel inlet port and an air inlet port therethrough, said casing having a chamber therein, said rotary member having a groove therein, said groove, as the member rotates, registering alternately with said fuel inlet port and said chamber, said rotary member having a second groove therein, said feeder having a mixing chamber at one end thereof, said second groove opening into said mixing chamber and registering, as the member rotates, with said first mentioned chamber, said member having a passageway connecting said air inlet port with said mixing chamber, and means for varying the capacity of said first mentioned chamber.

9. A fluid fuel feeder comprising a casing, said casing having a fuel inlet, means for supplying fuel to said inlet, a bearing in said casing, a rotary member mounted in said bearing, said casing and said member having grooves in their adjacent surfaces for conveying fuel along said surfaces,

said fuel inlet opening into the grooves of said casing, said casing having chambers therein adapted to register with the grooves of said member, means for varying the capacities of said chambers, and a fuel outlet opening into said grooves in said member.

10. A carbureter comprising a casing, said casing having a passageway therethrough, a rotary member mounted in said passageway, a second passageway through said member, one end of said second passageway adapted to receive air under pressure, and the other end adapted to be attached to an explosion chamber, a bridge across said second passageway, said casing having a fuel inlet therethrough, and said casing and said member having means for conveying fuel through said inlet onto said bridge.

11. A carbureter comprising a casing having a passageway therethrough, one end of said passageway adapted to receive air under pressure, a rotary bridge across said passageway, said bridge having an aperture therethrough, said casing having a fuel inlet therethrough, and means for supplying liquid fuel through said inlet and onto said bridge.

In witness whereof I hereunto affix my signature in the presence of two witnesses.

EZRA F. HOPKINS.
